FIG. 1.

FIG. 2.

FIG. 3.

Inventor

George A. Mead

UNITED STATES PATENT OFFICE

2,166,664

DRILL BIT

George A. Mead, Mansfield, Ohio, assignor to
The Ohio Brass Company, Mansfield, Ohio, a
corporation of New Jersey

Application May 27, 1938, Serial No. 210,351

9 Claims. (Cl. 255—71)

My invention relates to bits employed in drilling wells.

My invention is preferably provided with rotary cutters having teeth by means of which the material forming the bottom and sides of the hole is chipped and ground away as the drill bit is rotated. Other types of cutters may be used as for instance, flat cutters.

The drill bit is rotated by a drill or drive pipe 10 extending from the bit to the surface of the earth where it is driven by means of a rotating table.

In my invention the rotary cutters are supported in part by removable arms which may be readily detached from the bit for the purpose of renewing such arms as may be worn and also such cutters as need replacing.

One object of my invention is to provide means for holding the arms in assembled relation and which means will tend to more firmly secure the arms in position as the drill bit rotates as later herein explained.

Other objects will be made evident through the disclosure which follows.

25 In the drawing:

Fig. 1 is a side vertical view of my invention in partial section and shown attached to a drill pipe.

Fig. 2 is a vertical side view in section of my invention shown in Fig. 1 taken on the vertical plane at right angles to the vertical plane of Fig. 1, but without the drive mechanism shown in Fig. 1.

Fig. 3 is a horizontal section taken on the line 35 3—3 of Fig. 1.

Referring to Figs. 1 and 2, I show a hollow drill pipe 1 externally threaded on a taper and attached to a coupling 2 by like threads. The coupling is threaded internally at one end on a taper to receive the threaded tapered portion or stem 3 which forms an integral projecting part of the body 4.

The body is provided with four vertical and angularly disposed slots 5 and 6 to receive the 45 detachable arms 7 and 8 respectively and the body is provided with a grooved shoulder 9 projecting into each slot and having an inwardly and downwardly sloping side surface 10.

The body is also provided with a central axial passage 11 having a circumferential shelf 12 with an opening 13 therethrough.

The arms are each provided with an inwardly extending grooved shoulder 14 having an inwardly and upwardly sloping side surface to correspond 55 with the surface 10 on the body shoulder, the

shoulder 14 being arranged to interlock with the shoulder 9.

The upper end of each arm is provided with a flange 15 forming a depressed shoulder 16.

The body is further provided with a threaded 5 cylindrical portion 17 as distinct from the threaded tapered portion 3 and I prefer to thread the portion 17 with a left-hand thread while the portion 3 is threaded right-hand. The portion 17 may, of course, be threaded right-hand if desired. 10

In the past it has been the practice to place the collar 18 upon the tapered drive thread but I prefer to use a separate and cylindrical portion 17 for the collar as less close machining is necessary. 15

Mounted on the threaded portion 17 is a collar 18 threaded according to the portion 17 and provided with a flange 18' to interlock with the flange 15 on the end of the arm and to engage the shoulder 16 thereon. 20

When the arms are placed in position, with the shoulder 9 and 14 interlocked and the collar 18 in place and interlocked with the flange 15, the arms will be securely held against removal and they will be braced sideways by the side walls 25 of the slots 5 and 6.

The direction of rotation of the drill bit is usually clockwise looking down upon the bit when in its normal operating position and this tends to further secure or tighten the coupling 2 upon the bit while drilling as the threads are right-handed.

If the collar 18 and body 4 be threaded right-hand the friction between the collar and the side wall of the hole during drilling or between 35 the debris which collects around the drill bit and about the collar 18 will have a tendency to rotate the collar 18 relative to the body and hence unscrew it from the body, but by threading them left-hand, as previously pointed out, the friction 40 will tend to rotate the collar relative to the bit to further tighten the collar upon the arms during rotation of the bit in a clockwise direction.

In some designs of my invention the diameter of the collar 18 may more nearly approach the 45 diameter across the arms at the lower end of the bit than is shown in Fig. 1, therefore, the tendency for the collar to rotate relative to the bit in such a design would be greater as the friction upon the collar 18 and hence the force tending to rotate the collar would be more positive in action since the diameter of the collar is greater.

The end of the coupling 2 will tend to constantly move towards and into engagement with the collar 18 during drilling if the parts have 55

been accurately machined and will act as a lock for the collar, but this is not necessary when the collar is threaded left-hand as I propose.

If the portion 17 were threaded right-hand then any rotation of the coupling 2 in a clockwise direction (as previously described) relative to the bit, while drilling, will tend through friction between the coupling 2 and collar 18 to rotate the collar and move it into tighter engagement with the arms or at least will check any tendency of the collar to rotate in an anti-clockwise direction and thus prevent the arms loosening, providing the parts are so machined that the coupling engages the collar.

It will be evident that with my invention the arms will be held securely in place during drilling with a tendency toward the automatic tightening of the collar upon the arms and of the coupling 2 upon the collar 18 or upon the stem; in any event the collar tends to tighten upon the arms as the bit rotates in a clockwise direction should slack occur between such parts.

The arms 7 are each provided with a cutter 19, mounted on a stud 20 shown as an integral part 25 of the arm.

Mounted on and secured to the bit is a support 21 having a stem portion 22 extending into the passage 11 and having its upper end threaded to receive the nut 23 to hold the support in place with the shoulder 24 in engagement with the shoulder 25.

The support has a downwardly projecting arm 26 which has a through opening 27 to receive the shaft 28. The vertical central axis of the arm 26 is positioned to one side of the vertical axis x-x of the bit as shown in Fig. 2, thus permitting the use of a long and short cutter 29 and 30 respectively mounted on the shaft 28.

The shaft 28 has its ends mounted in openings 40 in the arms 8 and held in place by pins 31 and the studs 20 have their ends supported in recesses in the arm 26.

The openings 32 permit the use of a spanner wrench in tightening the collar 18 against the arms.

The support 25 has a passage 33 with side openings 34 through which water may be forced from above onto the cutters to clear them of debris and force the same to the surface of the ground 50 through the space between the drive pipe and the side wall of the hole being drilled.

While the general practice is to thread the body of the bit tapered to take the drill pipe, the body may be threaded straight.

If desired, the drive pipe end may be internally threaded on a taper and be directly attached to the body, thus omitting the coupling 2.

As my invention, I claim:

1. A drill bit comprising a body having a plurality of downwardly projecting arms, each arm being detachably secured to the body and carrying cutters at the lower ends thereof, interlocking shoulders on the arms and body and a collar mounted on the body to engage and interlock with the ends of the arms to prevent disengagement of the arms relative to the body, the body and the collar provided with cooperating left-hand threaded cylindrical portions whereby the collar may be moved into engagement with the arms by rotation of the collar in an anti-clockwise direction relative to the body and a threaded projecting stem on the body to receive a drive pipe whereby the bit is rotated.

2. A drill bit comprising a body, a plurality of detachable cutter carrying arms associated

with the body, threaded tapered means on the body for attachment to a drive mechanism to rotate the bit in a clockwise direction, a left-hand threaded cylindrical portion on the body, threaded clamping means mounted on the threaded cylindrical portion to engage and hold the arms in position on the body, the said clamping means being so arranged as to be engaged by the end of the drive mechanism to lock the clamping means in place when the bit is operated.

3. A drill bit comprising a body having a right-hand thread at one end to attach it to a driving mechanism, a plurality of arms detachably connected with the body and each adapted to support a cutter, the body having a left-hand thread adjacent one end of each arm, a clamping member mounted on the body and interlocked with the left-hand thread to engage and hold the arms in position, the attachment of the bit to the driving mechanism and the pressure of the clamping member upon the arms tending to increase independently of each other as the bit rotates in a clockwise direction.

4. A drill bit for sinking a hole in the earth and adapted for rotation in a predetermined direction by a driving mechanism comprising a body having a plurality of detachable cutter carrying arms, clamping means mounted on the body and engaging the arms to hold them in position and to take up any slack between the arms and body which may develop during drilling independent of the driving mechanism providing the clamping means is rotated in the opposite from the aforesaid direction relative to the body through engagement of the clamping means with the surrounding earth, and cooperating means associated with the body and clamping means to effect the aforesaid functions.

5. A drill for sinking a hole in the earth comprising a body, a plurality of detachable cutter carrying arms associated with the body, a threaded portion on the body for attachment to a driving mechanism to rotate the bit, a cylindrical portion on the body adjacent the said threaded portion, a clamping ring mounted on the cylindrical portion to engage and hold the arms in position on the body, means upon the surface of the cylindrical portion interlocked with means upon the clamping ring, the interlocking means between the clamping ring and the body being such that a tangential force applied to the periphery of the clamping ring through friction of the clamping ring with the earth as the bit rotates in a clock-wise direction will tend to rotate the clamping ring and move it longitudinally toward the arms.

6. In a drill bit for sinking a hole in the earth comprising a body, a plurality of demountable cutter carrying arms associated with the body, means on the body to receive a driving mechanism to rotate the bit in a clock-wise direction, a clamping ring mounted on the body in interlocking relation thereto to engage and hold the arms against becoming loose, the combination with the clamping ring and the body of means to interlock these parts together whereby the clamping ring will tend to move longitudinally of and toward the arms through tortional force applied to the clamping ring external of the bit and driving mechanism while the bit rotates in a clock-wise direction to take up slack or wear between the arms and clamping means which may develop while the bit is drilling.

7. A drill head comprising a body, a plurality

of demountable cutter carrying arms, threaded means on the body for attachment to a rotatable driving member to rotate the head in one direction, means to clamp the cutter carrying arms in position on the head, the said means including a clamping ring mounted on the body and provided with threads opposite in effect to the aforesaid threads whereby the resistance to rotation of the drill head during drilling will tend to effect a tightening of the drilling member upon the body and the engagement of the clamping ring with the surrounding earth during drilling will tend to tighten the clamping ring upon the arms and automatically eliminate any looseness between the arms and body and the clamping ring which may develop during drilling.

8. A central member for a drill bit adapted to support a plurality of cutter carrying arms comprising a body having a plurality of means spaced around its outer surface adapted to interlock with means on cutter carrying arms to assist in holding the arms in position on the member, a projecting tapered portion having its surface provided with a thread to receive threaded driving means whereby the driving means will tend to tighten upon the tapered portion when the member is rotated, a cylindrical portion be-

tween the threaded tapered portion and the interlocking means to receive a threaded collar to interlock with the arms to secure them to the central member, a thread on the surface of the cylindrical portion which is opposite in effect to that of the thread on the tapered portion of the member, arranged to cooperate with the threaded collar whereby the collar will be automatically moved through engagement with the surrounding earth to take up any slack which may develop between the arms and central member during the drilling operation.

9. A drill bit comprising a body, a plurality of demountable arms carrying cutters at the ends thereof, means on the body to attach it to a driving mechanism whereby the bit may be rotated in a predetermined direction, a clamping ring mounted on the body and movable longitudinally toward the arms when the clamping ring is rotated in the opposite direction to the said predetermined direction relative to the body to engage the arms and hold them securely in position on the body and means on the body interlocking with means on the clamping ring to affect the said longitudinal movement of the ring.
